(57) **CLAIM**

The ornamental design for a security cover for vending machine electronic locking motor drive, substantially as shown and described.

DESCRIPTION

FIG. 1 is a right front perspective view of a security cover for vending machine electronic locking motor drive showing our new design;

FIG. 2 is a front elevational view thereof;

FIG. 3 is a bottom plan view thereof;

FIG. 4 is a left side view thereof;

FIG. 5 is a right side view thereof;

FIG. 6 is a rear elevational view thereof;

FIG. 7 is a bottom plan view thereof;

FIG. 8 is a right front perspective of an alternate version thereof;

FIG. 9 is a front elevational view thereof;

FIG. 10 is a right front perspective view of another version thereof; and,

FIG. 11 is a front elevational view thereof.
